(57) CLAIM

The ornamental design for a holder for personal care items, as shown and described.

DESCRIPTION

FIG. 1 is a front perspective view of a holder for personal care items according to my new and ornamental design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dot broken lines show the boundaries of the claimed design and form no part of the claim. The evenly dashed broken lines show portions of the holder for personal care items that form no part of the claim.

1 Claim, 6 Drawing Sheets
